DENTAL TONGUE RETRCTOR

Ervin M. Funderburk, 1648 Providence Road,
Charlotte, N.C. 28806

Filed Apr. 12, 1974, Ser. No. 460,293

Term of patent 14 years

Int. Cl. D24—03

U.S. Cl. D24—1 D

FIG. 1 is a front elevation view of a dental tongue retractor showing my new design;

FIG. 2 is a side elevation view thereof;

FIG. 3 is a rear elevation view thereof;

FIG. 4 is a front elevation view of a second embodiment of the design shown in FIG. 1;

FIG. 5 is a side elevation view of the embodiment of FIG. 4; and

FIG. 6 is a rear elevation view of the embodiment of FIG. 4.

I claim:

The ornamental design for a dental tongue retractor, substantially as shown and described.
